C. NUHRING

FIRE EXTINGUISHER

Filed June 24, 1925

Fig. 1.

Fig. 2.

Inventor,
Charles Nuhring
By Arthur D. Ewald,
Attorney.

UNITED STATES PATENT OFFICE.

CHARLES NUHRING, OF CINCINNATI, OHIO.

FIRE EXTINGUISHER.

Application filed June 24, 1925. Serial No. 39,270.

My invention relates to fire extinguishers of the chemical type.

The principal object of my invention is to provide an extinguisher of improved and increased efficiency.

Other objects of the invention will appear from the following detailed description thereof.

In the drawings:

10 Figure 1 is a vertical section of one form of extinguisher constructed in accordance with this invention.

15 Figure 2 is a vertical section of another form of the extinguisher in accordance with this invention.

Referring to the type of extinguisher illustrated in Figure 1, the numeral 1 indicates a metal container having a base 2 upon which the same is adapted normally to rest, 20 and a rest 3 upon which it is adapted to be set when inverted for use. Inside the container 1 is a secondary container 4, the upper part of which is provided with a threaded flange 5 for a sealing ring 6. The ring 6 is 25 adapted to secure in position a thin strip of lead foil or similar easily perforated material 7 to seal the container 4. Inside the container 4 is a weight 8, the lower surface of which is flat so as to rest normally upon 30 the bottom of the container 4. The upper surface of the weight 8 is tapered as shown, so that the central portion thereof may protrude through the upper end of the container 4 when the sealing sheet 7 is ruptured by 35 means of a series of points 9 carried by the weight on its upper side. The ring 6 is provided with upright standards 10 between which is a base 11 for a bottle or jar 12, said standards being also provided with bands 40 13 to support the jar laterally. The jar 1 is provided with a loose stopper 14 which drops out by gravity when the device is inverted, the bands 13 serving to hold the jar from dropping when the device is in 45 this position. The container 1 is provided with the usual outlet 15.

Inside the container 1 is a solution of sodium bicarbonate 16 and the jar 12 carries a supply of sulphuric or other suitable acid, 50 by means of which when liberated the bicarbonate solution is caused to generate a gas to expel the solution through the outlet 15. Inside the container 4 I provide a supply of carbon tetrachloride. When the device is inverted the weight 8 drops, puncturing the sealing sheet or membrane 7 and

the carbon tetrachloride is liberated through the opening in the weight into the solution and thus expelled through the opening therewith.

60 In Figure 2 of the drawings I have illustrated an extinguisher of the type wherein air pressure is maintained in the device for expelling the extinguishing fluid at the desired time. In this construction two tanks 65 or containers 17 and 18 are provided, one of which, 17 for instance, may be provided with a solution of chloride of calcium, and the other with a supply of carbon tetrachloride. Air pressure is maintained in the 70 tanks by means of pipes 19 which extend substantially to the bottoms thereof. A three-way valve 20 of ordinary construction is arranged so that the air pressure may be supplied through said pipes or when desired 75 the solution may be expelled through the outlet hose 21 by means of such pressure. When so expelled the chloride of calcium and carbon tetrachloride are mixed.

80 The operation of the device in either form as above described will, it is thought, be apparent to those skilled in the art to which the same appertains. When the container or tank 1 is inverted the device illustrated in Figure 1 operates, in so far as 85 the sodium bicarbonate and acid are concerned, in the same manner as extinguishers of well-known construction now on the market. Simultaneous with the inversion of the tank, however, the carbon tetrachloride 90 is liberated into the solution and this when it becomes heated by the fire to be extinguished generates gas in great volume which serves very rapidly and expeditiously to extinguish the flame. I am aware that 95 carbon tetrachloride has heretofore been used for extinguishers, but where the same is employed by itself the gas is frequently generated prior to the actual application thereof to the fire, and thus the gases may be and 100 frequently are carried away by winds and thus fail of their object. By having the same mixed with the less volatile sodium bicarbonate or chloride of calcium the same is insured of actual application to the seat 105 of combustion before volatilization and thus the gas is formed where required for extinguishing purposes.

110 I am aware that numerous modifications may be made in the construction and ingredients employed in the fire extinguisher in accordance with this invention, and I

therefore desire to have it understood that such modifications as come within the spirit and scope of the appended claims are considered as of my invention, the basic principal or feature of which rests in the mixing or damping of the carbon tetrachloride with or by means of a less volatile liquid.

Having thus fully described my invention, what I claim as new and desire to secure by Letters Patent is:

1. In a fire extinguisher a normally isolated quantity of carbon tetrachloride, a normally isolated solution of sodium bicarbonate, and a normally isolated acid and means whereby said acid and bicarbonate of soda solution may be caused to mix to gen-

erate a gas to expel the same, and means whereby said carbon tetrachloride is caused to mix gradually with said solution during expulsion.

2. In a fire extinguisher, in combination with a tank containing a fire extinguishing solution, a second tank inside said tank, said second tank containing a quantity of carbon tetrachloride, means for sealing the contents in said second tank from said first tank means for generating pressure for expelling the solution from said first tank, and means whereby the said carbon tetrachloride may be discharged gradually into the solution in first mentioned tank.

CHARLES NUHRING.
